PINBALL GAME

Clarence H. Huenergardt, Cicero, Ill., assignor to
Raymond T. Moloney, Chicago, Ill.

Application March 20, 1935, Serial No. 12,022

4 Claims. (Cl. 273—121)

The present invention relates to an improvement in pin ball games.

These games comprise a cabinet containing a top play board inclined slightly from the horizontal so that balls projected to the upper end thereof may gravitate down the board, and if skilfully enough projected, to be trapped by scoring holes formed in the board. In some types of games, a manually released, rotatable scoring device is provided in the nature of a handicap means to give the player the advantage of an initial starting score before any balls are played by him.

The present structure is a variation of this idea in that either the balls may be played or optionally the auxiliary scoring device may be played to achieve a given score, the idea being not to exceed a certain score total. Or, alternatively, only a few of the total number of balls available may be played and the remainder of the score to be made, may be attempted by using the auxiliary score device. In this latter connection, if all available balls have not been played it is desirable to have some means operate from the auxiliary score means to make it impossible to project such balls as remain unplayed, so that the player is bound by his election to use the auxiliary score device instead of playing the unused balls.

Accordingly, the main object of the invention is to provide means operable when the auxiliary score device is used, to prevent play of any balls remaining.

Another object is to provide means for placing an obstacle in the ball projection passage to prevent the balls from being projected under the circumstances described.

Still another object is to cause automatic placement of the obstacle in position in the projection passage to prevent projection of remaining balls, when the auxiliary score device is operated.

Other important objects will later become apparent.

Briefly, these important objects are attainable in a pin ball game of the type described having a rotatable, or other operable auxiliary score device, the play board having a ball projection passage and a projector therein as shown in the drawings forming part of this application. When the auxiliary score device is operated means is operative therefrom to move an obstacle member across the projection passage to prevent projection of any balls remaining unplayed.

In the accompanying sheets of drawings illus-

trating one practicable embodiment of the invention:

Figure 1 is a general plan view, on a reduced scale, of the front half of a pin ball game showing the auxiliary score device associated therewith; 5

Figure 2 is an enlarged plan view of the front portion of the game with the top, or play board partly broken away to illustrate the operating mechanism for the score device and the associated obstacle for making projection of balls impossible; 10

Figure 3 is another top plan view of the mechanism as it appears looking down from the line 3—3, appearing in Figure 4;

Figure 4 is a central, side sectional view through 15 the game taken along the line 4—4 of Figure 1, looking in the direction of the arrows; and,

Figure 5 is a detail side elevational view, partly in section, to show the ball lifter, taken along the line 5—5 of Figure 2, looking in the direction of 20 the arrows.

The general game organization appears in Figure 1, where it will be seen that a cabinet 10 is provided, having a front wall 11 carrying the usual coin slide 12, ball lift operator 13, and ball projecting plunger 14. As shown also in Figure 4 the cabinet carries a game board 15 sloped slightly from the horizontal in the usual manner, with the lower end of said board disposed adjacent the front wall 11. 25

The game board is cut out appropriately to form a ball rolling play field 16 having a number of holes 17 formed therethrough to trap balls in a manner well understood. At the lower end of the field 16 is an "out" ball pocket 18 to receive spent balls that miss the holes 17. The lower end of the board 15 has a circular depression 19 on its top face to receive a rotatable disk 20 having its marginal edge marked off with numbers to serve as score designations. 30

The ball projector 14 is located in the customary manner at the lower end of a ball projecting passage 21 at the right hand edge of the game board. An abutment 22 in the passage serves to hold the balls in position to be struck 45 by the plunger.

As shown in Figure 4 the cabinet side walls carry brackets 23 for slidably mounting an under ball supporting panel 24, which holds balls dropping into the holes 17 and 18, so that they can be viewed from the top of the board 15. This panel 24 is provided with the usual ball escape openings, not shown, for each of the holes 17 so that when said panel 24 is shifted rearwardly, the balls in the holes 17 drop through the panel 24 onto a lower 50 55

stationary ball routing panel 25, which directs the balls to a transversely inclined trough 26.

This trough 26 leads the balls toward the right hand wall of the cabinet 10 and into a groove 27 formed therein as shown in Figure 5. Adjacent the groove is mounted a pivoted ball lifter 28 operable by the plunger 13 to raise balls, one at a time, from the lower end of the trough 26, up the groove 27 and into the passage 21 on the board 15, said elevated balls then gravitating a short distance to lodge against the abutment 22 to be in position for projection by the projector 14 in a manner well known in this art.

A spring, not shown, and as common in this art, always exerts a force to hold the panel 24 in its forward position, which is shown in Figure 4. This panel 24 carries a forwardly extending bracket 29 in line with the coin slide 12 so that when the latter is coin released and pushed rearwardly into the cabinet, the slide 12 abuts the bracket 29 to push and slide the panel 24 to release the trapped balls in the holes 17 in the manner heretofore described. Balls in the "out" pocket 18 drop over the front edge of said panel 24 into the trough 26.

Below the dial 20 and under the board 15 the side walls of the cabinet 10 carry a stationary cross plate 30, which plate 30, substantially midway between its ends carries a stationary vertical shaft 31, supporting on a suitable bearing for turning movement, a sleeve 32 having a ratchet wheel 33 formed at its lower end slightly above the plate 30. Secured by a plate 34 and a screw 35 to the top of said sleeve 32 is the rotatable, numbered dial 20 heretofore described. The board 15 carries a stationary pointer 36 adjacent the periphery of the dial.

The under side of the plate 30 carries a pin 37 to which is pivoted one end of a rearwardly extending lever 38, which in turn has pivotally connected to its rear end, a transversely extending lever 39. The free end of the lever 39 carries an upstanding pin 40 carrying a roller 41. A spring 42 connected between the lever 39 and plate 30 serves normally to pull the lever 39 to its forward position as shown in Figure 2. A slidably mounted plunger 43 is mounted in the front wall 11 and guided in a bracket 44 carried by the plate 30. The rear end of the plunger 43 carries a head 45 to abut an abutment 46 carried on the under side of the lever 39.

The pin 40 at the left hand end of the lever 39 extends upwardly through a guide slot 47 formed in the plate 30 as shown in Figure 2. The top side of the plate 30 carries a vertical pin 48 to which is pivoted, intermediately of its ends, a lever 49. A spring on the pin 48 has one leg 50 bearing against a pin 51 on the lever, and another leg 52 bearing against a pin 53 on the plate 30. The left hand end of the lever 49 carries a pivoted, spring pressed, trigger 54 having an extension 55 in the path of movement of the pin 40 as it moves through the slot 47. A stop pin 56 on the plate 30 is positioned forwardly of the trigger 54 to limit the forward movement of the left hand end of the lever 49.

The right hand end of the lever 49 carries a pivoted, spring pressed, forwardly extending pawl 57 having a pin 58 on its under side. When the pawl 57 is moved forwardly by the lever 49 the pin 58 guides along the left hand side of a vertical wall 59 on a spring pressed pivoted lever 60 carried by a pin 61 below the plate 30 and in an opening 62 formed therein. As the lever 49 moves the pawl 57 forwardly its pin 58 eventually

rides off the front end of the wall 60, causing the pawl to engage the ratchet wheel 33. The spring 50, 52 then presses the lever 49 to move the pawl 57 rearwardly to turn the ratchet 33 and spin the score dial 20, all in the manner more specifically disclosed in my co-pending application, Serial Number 749,602, filed October 23, 1934 for "Scoring device for games and the like".

Below the plate 30 (see Figures 2 and 3) at its left hand end is a pivot pin 64 carrying pivotally a two armed lever having an arm 65 and an arm 66. A stop pin 67 is provided to limit the pivotal movement of the lever in the right hand direction under the influence of a spring 68 pressing the lever. The rear end of the arm 65 is widened 15 cut and notched at 69 to receive the roller 41 heretofore described.

Adjacent the lever 65, 66 the under side of the plate 30 carries another pivot pin for pivotally mounting a trip lever 70 intermediately of its ends, one end of the lever 70 being stopped by a pin 71, while the other end is slotted, slidably to receive a longitudinal rod 72 having a bent end 73 and carried by the slidable panel 24, as shown.

The abutment 46 on the lever 39, heretofore described, is engageable with one leg of a bell crank lever 74 pivoted to a pin 75 under the plate 30. The other leg of this bell crank lever carries a roller 76, which engages the downwardly bent end of a transverse slide bar 77 guided by a pair of slots 78 in the bar and pins 79 carried by the under side of the plate 30. This bar is normally pulled to the left, as seen in Figure 3, by a spring 80. The right hand end of this horizontal flat bar has secured to it, as by welding, a vertical plate 81 movable with the bar in a vertical slot formed in the under side of the board 15 adjacent the projection passage 21, and slightly rearwardly of the abutment 22 in said passage. A 40 glass panel 82 encloses the top of the cabinet 10.

This completes the detailed description of the parts. The use and operation of this mechanism will now be given.

In operating the game it will be understood that only a predetermined number of balls are sealed in the cabinet and available for play. We will assume then that there are only five balls. In starting the play these five balls will be either in the trough 26, or scattered, with some in said trough, while others are in the holes 17 or pocket 18. Such balls in the traps 17, 18 are supported by the slide panel 24.

By operating the coin slide 12 the panel 24 is shifted to release the balls from the traps to cause them to roll into the trough 26, where they are available to be elevated one by one, by the lifter 28 into the projection passage 21 and against the abutment 22 therein. Operation of the plunger projector 14 shoots these balls to the rear, high end of the board 15 in the usual way, such balls then gravitating down the play field 16 to lodge in the holes 17, which have designated, numerical scoring values.

After two or three of the balls have been so played the player may decide to complete the scoring by operating the numbered dial 20, it being remembered that the player's purpose is to achieve a score total which will not exceed a given figure. Such figure may be made by trapping several balls and adding to the score so obtained the chance, additional score determined by spinning the dial wheel 20.

Accordingly, the player pushes the plunger 43 into the cabinet 10, causing the head 45 to abut 75

the abutment 46 to move the lever 39 about its pivotal connection to the lever link 38 and about the pivot 37. Thus, the left hand end of the lever 39 moves the pin 40 thereon rearwardly 5 through the guide slot 47 formed in the plate 30. This pin 40 thereupon pushes on the extension 55, causing the trigger 54 to move rigidly with the lever 49 about the pivot pin 48. Thus, the right hand end of the lever 49 moves forwardly to move 10 the pawl 57 ahead, said pawl being guided by its pin 58 along the vertical wall 59 of the pivoted member 60. This movement has placed the spring 50, 52 under tension. When the pin 58 rides off its guide the spring pressed pawl 57 is urged into engagement with the ratchet wheel 33.

In the meanwhile the plunger 43 has moved the lever 39 to the position shown in Figure 3 and as the spring 68 normally urges the V-lever 66, 65 to the right it so happens that the roller 41 readily locks in the notch 69 in the lever arm 65, thus locking the lever 39 against the tension of its spring 42. At this position of the lever 39 its abutment 46 has also engaged the bell crank lever 74 to push the slide bar 77 to the right and there- 20 by slide the obstacle member 81 across the passage 21. In this position the member 81 obstructs the passage to prevent elevated balls from rolling to the abutment 22. Thus, while balls may be elevated into said passageway 21 they cannot 25 be projected. Therefore, the projector 14 is made ineffective and any unplayed balls remaining cannot now be played, one of the balls being shown held back by the obstructor 81 in Figure 3.

While this setting of the obstacle has taken place the pin 40 has been guided to the left by the shape of the slot 47 to such an extent that the extension 55 is freed from the pin 40. As a result, under the pressure of the tensioned spring 40 52, 50 the lever 49 swings back sharply to its original position as shown in Figure 2, thus moving the pawl 57 rearwardly to turn the ratchet wheel 33 and spin the dial 20. The dial comes to rest eventually with one of its numerals aligned 45 with the pointer 36. In this fashion a score number is designated which is to be added to the score achieved by trapped balls in the holes 17 to make up the final game score total.

The under lever 39, of course, remains in the locked position shown in Figure 3, during and after spinning of the disk 20, and the parts remain so until another play is started by releasing the coin slide 12. When the coin slide 12 is pushed rearwardly it moves the ball releasing 50 panel 24 rearwardly and with it the rod 72. The hook end 73 of said rod hits the trip lever 70 to pivot the same, thereby swinging the arm 66 and arm 65 to the left to release the roller 41 from the notch 69. Instantly now the spring 42 pulls 55 the lever 39 forwardly to its normal starting position as shown in the dotted lines in Figure 2; at the same time the spring 80 is operative to pull the bar 77 back to remove the obstacle member 81 from the passage 21 in a manner that 60 will be readily understood.

The spring 68 serves to return the two-armed lever 65, 66 to a position stopped against the pin 71 and the arm 66 itself returns the trip 65 lever 70 to its normal position stopped against the pin 71. When the panel 24 returns to its normal forward position in the cabinet 10 the rod 72 merely slides through the trip arm 70.

The extension 55, of course, became positioned in front of the pin 40 as it returned before the pin. Obviously for another operation of the

dial 20 the extension 55 must be to the rear of the pin 40 in the slot 47. It is for this reason that the trigger 54 is spring pressed and pivoted to the lever 49 as it permits the pin 40 as it returns to its forward position to pass 5 the extension 55 by pivoting the trigger independently of the lever 49 as described in my aforementioned co-pending patent application.

The form of dial 20 shown is of no materiality as a turning pointer may be used with a stationary dial as an obvious substitute.

From this disclosure it can now be seen that an improved game apparatus has been provided which is simple and fool proof in operation, and achieves all of the desirable objects heretofore 15 recited.

It is the intention to cover all such changes and modifications of the illustrative form of the invention disclosed which do not depart from the spirit and scope of my invention as indicated by 20 the appended claims.

What is claimed is:

1. A marble rolling game having a game board provided with ball receiving holes and a ball projection passage, means to elevate balls from below the board into the passage, a projector in the passage to project balls onto the board, a movable ball supporting panel below the board, an obstacle member movably mounted below the board and adapted to enter the passage to prevent projection of balls by the projector, operator controlled mechanism for moving the obstacle member to a position in the passage to prevent projection of balls through the passage, means to releasably lock the obstacle member 35 in such position, and coin released means to move the panel, movement of the panel operating connections to cause movement of the obstacle member to inoperative position whereby balls may once more be projected through the 40 passage.

2. The combination with a pin and marble game having a substantially horizontal game board including a ball projection passage and means for projecting a ball through the passage onto the board, of a movably mounted obstacle device included in the game and normally disposed in an inoperative position relative to the passage to permit passage of balls through the passage when the same are projected therethrough by the projector, and operator controlled means included in the game and operable to move the obstacle device to a position into the passage to prevent further projection of balls through the passage by the projector.

3. The combination with a pin and marble game having a substantially horizontal game board including a ball projection passage and means for projecting a ball through the passage onto the board, of a movably mounted obstacle device located beneath the board and movable to positions for either obstructing or not obstructing said passage to prevent or permit projection of balls therethrough, a spring normally holding said device in its non-obstructing position, manually movable means included in the game to move said device to its passage obstructing position against the pull of said spring, and a releasable latch operatively associated with the device to retain it in its obstructing position.

4. The combination with a pin and marble game having a substantially horizontal elongated game board including a ball projection passage along one side thereof, a projector in 75

the passage for projecting balls therethrough onto the board, a transversely disposed member movably mounted below the board for movement from an inoperative position to a position where one end thereof obstructs the passage to prevent balls from being projected through the passage, resilient means urging said member to inoperative position, a manually moved plunger included

in the game including mechanism for moving the member to its passage obstructing position, means to latch the member releasably in its obstructing position, and means for releasing the latch to cause the resilient means to return the member to its normal inoperative position. 5

CLARENCE H. HUENERGARDT.
